UNITED STATES PATENT OFFICE

2,415,721

PAPER BOX CONSTRUCTION

Sterling E. Arner, Charlotte, N. C., assignor to
Old Dominion Box Company, Lynchburg, Va., a
corporation of Virginia

Original application July 19, 1943, Serial No.
495,288. Divided and this application June 21,
1944, Serial No. 541,346

1 Claim. (Cl. 229—5.5)

1

This invention relates to a paper container and more especially to a cylindrical container such as used for packaging half-pound and one pound quantities of tobacco, although it is to be clearly understood that this type of container can be used for any other purpose desired.

It is an object of this invention to provide a container having a hermetically sealed reinforced bottom and one which presents a very neat appearance.

This is a divisional application forming a part of original application, Serial Number 495,288, filed July 19, 1943, Patent No. 2,356,194, Aug. 22, 1944.

It is another object of this invention to provide a container having the wrapper folded over both the upper and lower edges thereof and embedded between the inner and outer layers of the walls of the container and the upper and lower end thereof.

It is another object of this invention to provide a container having a bottom whose outer edge is flush with the inner wall of the shell of the container with a sheet covering the bottom and the lower edges of the inner shell of the container and being turned upwardly and embedded between the inner and outer shells of the container, the outer shell of the container having a covering whose upper and lower edges are turned inwardly and are embedded between the outer and inner shells of the container.

It is another object of this invention to provide a container having a reinforced bottom member with a label covering the bottom member and embedded in the lower side walls of the container, with a reinforced bottom member disposed within the container, the reinforced bottom member being glued to the initial bottom member by a special type of pattern gluing which prevents uneven expansion of the bottom members and also which gives more perfect gluing of the additional bottom member to the regular bottom member.

Some of the objects of the invention having been stated, other objects will appear as the description proceeds, when taken in connection with the accompanying drawings, in which:

Figure 1 is an elevational view of the container with the bottom portion thereof broken away;

Figure 2 is an enlarged vertical sectional view of the lower portion of the structure shown in Figure 1 before the parts are compressed together;

Figure 3 is a view similar to Figure 1, but showing an additional bottom member disposed within the container;

Figure 4 is an enlarged detail vertical sectional view of the lower portion of the structure shown in Figure 1 before the parts are compressed together;

view of the lower portion of Figure 3 before the parts are compressed together;

Figure 5 is a cross-sectional view taken along the line 5—5 in Figure 1;

Figure 6 is an elevational view of one side of the bottom member.

Referring more specifically to the drawings, the numeral 10 indicates the inside side wall of the box which projects above the outer side wall 11, and a suitable cover is adapted to fit over the upper portion of the inside side wall 10, and have its lower edge fit snugly against the upper edge of the outside wall 11. The outside side wall 11 is covered with a suitable wrapper 12 on which the trade-mark or other suitable printed matter is placed. The wrapper 12 is turned inwardly between the inner and outer side walls at the upper and lower ends as indicated by the upturned portion 13 in Figure 2. The top edge of the wrapper is likewise turned inwardly and downwardly between the inner sidewall 10 and the outer side wall 11. Fitting snugly within the inner side wall 10 is a bottom member 14 which is secured in position by means of a bottom label 15 which has its edges turned upwardly and secured by any suitable means such as an adhesive between the inner and outer side walls as at 16. This bottom retaining label 15 is usually composed of what is termed as white face kraft paper, so as to give the proper strength for retaining the bottom 14 in position.

In Figures 3 and 4, the same reference characters apply as have previously been used in describing Figures 1 and 2, and in Figure 4, there is an extra bottom member 17 fitted within the box, as it is noted that in Figures 3 and 4 this extra bottom member is disposed immediately above the original bottom member. This extra bottom member rests on the inside top surface 40 of the regular bottom 14. This extra bottom 17 is secured in position by having a flush fit at its edges against the inner wall of the inner side wall 10 and it also has suitable adhesive such as glue placed on its side which is disposed next to the regular bottom 14.

The pattern gluing used on the surfaces between the members 14 and 17 may be of any desired formation, but I have found that by using the pattern gluing as shown in Figure 6 that I obtain a very finished product without uneven expansion of the two bottom members of the box, and when an extra bottom is used, the two bottoms are more securely and permanently adhesively bound together when pattern gluing is employed. This pattern gluing is especially

adaptable in a structure of this type as it prevents undue expansion, due to moisture, in one direction more than another, and provides uniform expansion on account of moisture and therefore prevents buckling and wrinkling. I have found that concentric and radially disposed pattern gluing is very desirable in the manufacture of boxes of this type. In the form shown, I provide a plurality of concentric rings 25 and 26 of adhesive such as glue, and a plurality of radially disposed strips of adhesive 27 extending between the two concentric rings 25 and 26. When the disk is moistened, and adhesively secured to another member in face to face relation, this type of pattern gluing results in even application, and prevents any wrinkling whatsoever.

In Figures 2 and 4, the bottom structure of the box is shown on an enlarged scale with the inner and outer walls separated, that is before the parts of the box are placed in a suitable press and the parts compressed together, while in Figures 1 and 3 the parts are shown in a position before compression takes place.

In assembling the box as shown in Figures 1 to 4 inclusive, the inside wall 10 has the bottom 14 inserted therein and the sheet of material 15 is then applied by overall gluing, thus the periphery 16 projects straight outwardly. This periphery also has glue on both surfaces thereof which are adapted to contact the outer periphery of the inside wall 10, and the inner periphery of the outside wall 11. The outer wall 11 has previously been formed by applying the covering portion 12 by means of suitable adhesive and with the upper and lower edges of the covering portion 12 turned inwardly and downwardly and upwardly as the case may be as indicated at 13. Suitable adhesive is applied to the interior surface of wall 11, and then wall 11 is slid upwardly in Figure 2 over the wall 10, and this tucks the extension 16 tightly against the outer surface of wall 10, and although in the drawings there is shown a space between walls 10 and 11, it is really a very tight fit, and therefore, the adhesive on the inner surface of the wall 11 causes walls 10 and 11 to be tightly bound together, and of course somewhat greater pressure is present at the lower ends of the walls 10 and 11 which firmly causes

the folded portions 13 and 14 to be tightly secured together by adhesive which is present on account of the fact that adhesive has been wiped off the inner surface of the wall 11 as it passes by folded portion 16.

In the drawings and specification, there has been set forth a preferred embodiment of the invention, and although specific terms are employed, they are used in a generic and descriptive sense only, and not for purposes of limitation, the scope of the invention being defined in the claim.

I claim:

15 A circular paper box having inner and outer side walls secured to each other, a circular bottom fitting snugly within the lower end of the inner side wall, a sheet of paper adhesively secured to the lower surface of the bottom member, and having its outer edge folded up and secured between the inner and outer side walls of the container, the outer side wall having a cover whose upper edge is tucked down between the inner and outer side walls, and whose lower edge is turned upwardly and secured between the inner and outer side walls, and an additional bottom member disposed within the inner side wall, and adhesively secured to the first-mentioned bottom, and having its periphery fitting tightly against the inside surface of the inner side walls, the adhesive on the additional bottom member being in the form of a plurality of concentric rings with radially disposed strips of adhesive extending between the rings.

STERLING R. ARNER.
